Patented June 15, 1965

201,361

COMBINED DATA CONVERTER AND PRINTING APPARATUS

Edward R. Wiener, Rochester, Minn., assignor to International Business Machines Corporation, New York, N.Y., a corporation of New York

Filed Nov. 4, 1963, Ser. No. 77,265

Term of patent 14 years

(Cl. D26—5)

FIG. 1

Des. 201,361

PAGE 2

FIG. 2

FIG. 3

FIG. 4

FIG. 6

FIG. 5

FIG. 1 is a perspective view of a combined data converter and printing apparatus showing my new design;

FIG. 2 is a front elevational view thereof;

FIG. 3 is a plan view thereof;

FIG. 4 is a right side elevational view thereof;

FIG. 5 is a left side elevational view thereof; and

FIG. 6 is a rear elevational view thereof.

The essential features of my design reside in the portion shown in solid lines.

I claim:

The ornamental design for a combined data converter and printing apparatus as shown and described.
